UNITED STATES PATENT OFFICE.

FRANCIS R. DYKE, OF DARTMOUTH, NOVA SCOTIA, CANADA.

BUOY-LAMP.

1,313,172.

Specification of Letters Patent. Patented Aug. 12, 1919.

Application filed November 13, 1917. Serial No. 201,808.

To all whom it may concern:

Be it known that I, FRANCIS R. DYKE, a subject of the King of Great Britain, residing at Dartmouth, in the Province of Nova Scotia and Dominion of Canada, have invented certain new and useful Improvements in Buoy-Lamps; and I do hereby declare the following to be a full, clear, and exact description of the invention, such as will 5 enable others skilled in the art to which it appertains to make and use the same.

This invention relates to improvements in buoy lamps specially designed for use in lighting up cable buoys during night operations on submarine cable repair work, and the invention has for its primary object to provide an electrically operated lamp equipped with a clock controlled circuit closer for automatically making and breaking 10 the circuit to the electric lamps at predetermined time intervals.

Another object is the provision of a device of this character, in which the parts are fully protected against the action of 15 the elements, but are readily accessible for repair or replacement.

With these and other objects in view, the invention consists in the novel combination and arrangement of parts hereinafter more 20 fully described and claimed and set forth in the accompanying drawings, in which:

Figure 1 represents a front elevation of the lamp,

Fig. 2 represents a vertical sectional view 25 therethrough,

Fig. 3 represents a horizontal sectional view taken through the casing of the lamp in a plane above the partition or shelf therein,

Fig. 4 represents a horizontal sectional 30 view through the lamp globe,

Fig. 5 represents a fragmentary front elevation of the clock mechanism, the indicating disk being removed,

Fig. 6 represents a detail sectional view on 35 the line 6—6 of Fig. 2, and

Fig. 7 represents a perspective view of the rotary and spring contact elements of the circuit closer also illustrating diagrammatically the electrical circuit to the lamps.

Referring to the drawings in detail wherein similar reference numerals designate corresponding parts throughout the several views, the numeral 10 indicates a substantially rectangular casing having an open 40 front engaged by the closure plate 11 provided with a rabbeted edge receiving a gas-

ket 12 to prevent the admission of water or moisture to the interior of the casing. The vertical edges of the front plate 11 are formed with a plurality of pairs of spaced 60 ears 13 receiving the pivoted bolt shanks 14 carried by the casing 10 on which thumb nuts 15 are threaded to forcibly draw the front plate against the open front of the casing.

The casing 10 is provided with internal horizontal flanges 16 supporting the removable partition or shelf 17, which divides the interior of the casing into clock mechanism and battery receiving chambers 18 and 19 respectively, and the top of the casing is provided with a circular flange 20 receiving the globe or lens 21 for the incandescent lamps, which will be hereinafter more fully described. A top plate 22 covers the upper 65 open end of the globe 21 and the lower surface thereof is preferably polished to provide a reflector for projecting the light rays from the incandescent lamps downwardly with relation to the casing 10. The top 70 plate, as stated, forms a closure for the upper end of the globe 21 and it is secured in position by integral vertically projecting studs 23 carried by the top of the casing 10 and coacting with thumb nuts 24.

The angular terminals of a handle 25 are pivotally secured by straps 26, carried by the top plate 22 and the casing may be secured in position upon a buoy staff or other support by eye-bolts 27 carried by one side wall 75 thereof.

The top wall of the casing 10 is provided with an opening 28 receiving the lamp support 29 having a flanged base 30, which is seated against the front face of the top wall 90 of the casing and is bolted or otherwise secured thereto as indicated at 31 in such manner that it can be conveniently removed when necessary.

A forked arm 32 carrying lamp sockets at 100 its upper terminal is positioned in the support 29 and receives the incandescent lamps 33.

A plurality of electric batteries 34 are supported in the lower chamber 19 of the 105 casing and are preferably connected in multiple series. One pole of the battery is connected directly by a conductor 35 with the lamps 33, and the other conductor 36 having connection with the lamps is connected 110 with a binding post 37 secured in an insulator 38, which latter is carried by the casing

of a clock mechanism 39. A second binding post 40 is fastened to the insulator 38 and is electrically connected by a conductor 41 with the other pole of the batteries 34.

5 The arbor 43 of the clock mechanism 39 is provided with an integral collar 44 constituting an abutment for the disk 45, which is preferably constructed of insulating material and is secured in position upon the 10 arbor 43 by the nut 46. An indicator disk 47 suitably marked to represent the hours of the day is positioned against the front surface of the disk 45 and the latter may be readily adjusted upon the arbor 43 by simply loosening the nut 46.

20 A portion of the periphery of the insulating disk 45 is cut away and a segmental contact plate 48 is set into the recess and pivotally secured therein. A pair of spaced spring contact fingers 49 are secured to the insulator 38 and are connected, respectively, with the binding posts 37 and 40. The spring contact fingers 49 are disposed in spaced relation and thus interrupt the circuit to the 25 lamps 33, but as the free terminals of the fingers are engaged by the segmental contact plate 48 an electrical connection is established between the fingers and the circuit to the lamps 33 is completed.

30 In order that the lamps 33 may be caused to burn for varying predetermined periods, each buoy lamp is equipped with a series of interchangeable disks 45 provided with segmental contact plates 48 of varying lengths. 35 For instance, when it is desired to maintain the lamps 33 in operation for ten hours, a disk 45 having a segmental contact plate 48 of sufficient length to remain in contact with the spring arms 49 for ten hours is selected, 40 and in adjusting the disk so that the contact between the spring fingers 49 and plate 48 may be made at a predetermined time, the indicator disk 47 is utilized in properly adjusting the insulating disk 45 upon the 45 arbor 43.

What I claim is:

50 1. In circuit controlling means, a clock mechanism, a disk of electrical insulating material mounted on the main arbor of said mechanism for rotation therewith, a contact strip carried by said disk and extending a predetermined distance about the same, spaced contact fingers mounted in predetermined relation to the arbor of the clock mechanism and in rubbing contact with the peripheral surface of the disk so as to engage said contact strip during rotation of said disk, a setting disk mounted on the arbor adjacent the first mentioned disk and graduated to indicate time intervals, and means

for releasably securing said setting disk and said first mentioned disk upon the arbor so as to permit the disk carrying the contact strip to be turned about the arbor so as to space the forward edge of the contact strip a predetermined time interval in back of the point of contact between the disk and the contact fingers indicated by the setting disk.

2. In circuit controlling means, a clock mechanism, a disk of electrical insulating material mounted on the main arbor of said mechanism for rotation therewith, a contact strip carried by said disk and extending a predetermined distance about the same, spaced contact fingers mounted in predetermined relation to the arbor of the clock mechanism and in rubbing contact with the peripheral surface of the disk so as to engage said contact strip during rotation of said disk, a setting disk mounted on the arbor adjacent the first mentioned disk and graduated to indicate time intervals, and means for releasably securing said setting disk and said first mentioned disk upon the arbor so as to permit the disk carrying the contact strip to be turned about the arbor so as to space the forward edge of the contact strip a predetermined time interval in back of the point of contact between the disk and the contact fingers indicated by the setting disk, said securing means being adapted to permit complete removal of the contact strip carrying disk from the arbor shaft so as to permit replacement thereof by another contact disk having a contact strip of different length.

3. In circuit control means, a clock mechanism including an arbor shaft, a disk of electrical insulating material mounted on said shaft, the shaft being provided with an annular shoulder remote from one end thereof, a contact strip carried by the disk and extending circumferentially thereof, an insulating block, spaced contact fingers carried thereby and in rubbing engagement with the peripheral surface of the disk, and a securing nut screwed upon the end portion of said shaft and serving to force the disk into tight frictional engagement with the shoulder of the shaft, said shoulder and nut co-operating to releasably secure the disk upon the arbor shaft.

In testimony whereof I affix my signature in presence of two witnesses.

FRANCIS R. DYKE.
